UNITED STATES PATENT OFFICE

FRITZ HEYNER, OF HEIDELBERG, GERMANY, ASSIGNOR TO FRANZ KRUCKENBERG, OF HEIDELBERG, GERMANY

SUPPORTING ARRANGEMENT FOR THE RUNNING RAILS OF HIGH-SPEED SUSPENSION RAILWAYS

Application filed April 30, 1928, Serial No. 274,090, and in Germany May 4, 1927.

The invention relates to a supporting arrangement for the running rails of high speed suspension railways. The running rails here form an unbroken continuous length, without joint gaps. As already pointed out in the U. S. A. Patent 1,734,865, November 5, 1929 (Ser. No. 173,197), with changes in temperature, considerable stresses arise in these rails. It is therefore desirable to provide a line constructed in such a manner with some security for the event of a break taking place through very low temperature. The free ends of the rail formed by the break must then be held in such a manner that the gap between them is kept small enough to permit safe operation. In contradistinction to the parent invention, in which to ensure this result a longitudinal rail carrier is used, here the characteristic feature of the invention for achieving this purpose consists in that this longitudinal carrier is omitted and the main structure thus simplified and lightened. This result is based on the interposition of transmission members between the adjacent ends of two main carrier sections and the appertaining part of the running rail in such a manner that the transmission members can move freely during temperature changes, but bear against abutments on the respective main carrier ends, when the aforementioned lowest possible temperatures occur.

In the accompanying drawing an example shows how the transmission members between the adjacent ends of the main carrier sections and the corresponding part of the running rail are interposed, in order to obtain the described result.

Figure 1 shows in perspective a section of the main carrier and two adjoining sections of the main carrier.

Figure 2 shows the structural work on an enlarged scale and entirely diagrammatically, at ordinary temperature.

Figure 3 shows the structural work in the same manner at raised temperature.

Figure 4 shows the structural work in the same manner at the lowest temperature to be expected, and

Figures 5, 6 and 7 are three further forms of details of the structural work.

The main carrier sections are firmly fixed to the ground at their centres by supports 12, while movable supports 13 are movable to permit free movement (shortening and lengthening) of the main carrier sections 11 under the action of temperature changes. The continuous running rail 16 is rigidly secured by means of a strut structure 14 to the part of the main carrier adjacent the support 12, while at other places the rail length 16 is supported from the main carrier 11 by lateral carriers 15 which can yield in the horizontal plane. At the ends 21 and 22 of the main carriers the running rail 16 is connected to the respective main carrier section by transmission members 19. A hinged joint point is indicated by 20. The other end of each transmission member 19 is connected in the illustrated example to the respective end of a main carrier section 21 or 22 by a hinge 23. On the ends 21 and 22 of the main carriers 11 opposite the transmission members are abutments 24. At normal and raised temperatures there is a space between the transmission members 19 and the abutments 24 (Figures 2 and 3). At reduced temperatures—preferably at the lowest to be expected—the transmission members 19 can bear against the abutments 24 (Figure 4). If now for example at this temperature a break takes place for any reason at 25 then the rail to the right is held by the struts 14. On the other side this is effected by the transmission member 19 which bears on the respective abutment 24. In place of the broken rail therefore a part of the main carrier which transmits the rail temperature stresses.

The transmission members naturally can be otherwise formed and differently connected to the respective parts of the running rail and the main carrier section. In Figure 5 a second form of these transmission members is shown. Here they consist of the bars 26 and 27. Each bar 26 is hinged to the rail 16 and the corresponding main carrier section, while the bar 27 is only hinged to the rail. Its other end is slidably borne in a guideway

29 on the main carrier section 11 by a sliding pin 28. At the lowest temperature to be expected the sliding pin 28 bears against the end 30 of the guideway 29. This end 30 will then act in the same manner as the abutment 24 in the example of Figures 1 to 3.

10 The development of additional forces in the rail by the connections of the rail to the transmission members and the fixed points, must naturally be avoided. Similarly the resilient condition of the rail must be as fully maintained as possible.

15 A connection avoiding these objections is shown in Figure 6. The transmission member 19 engages with its end in an opening 31 in the rail. Strengthening plates 32 and fitting pieces 33 fix the transmission member and prevent lateral movement. A horizontal movement of the rail in relation to the member 19 is not excluded however since the end of the latter engages in the opening 31 of the rail 16 with horizontal play. The struts 14 at the centres of the main carrier sections 11 can be connected to the rail in the same way.

20 A third form of transmission member is shown in plan in Figure 7, wherein the rail 16 is shown in horizontal section on the centre of the web. Here outrigger's arms 34, shown as triangular frames rigidly secured to the main carrier ends act as transmission members. Their ends 35 enter a longitudinal slot 36 in the rail 16, which is again preferably strengthened by fish plates at this point. In accordance with the invention the slot 36 is so long that the outrigger ends 35 only bear against the edges of the slot under conditions of maximum or minimum temperature. At all other low temperatures they have more or less play in the slot and naturally also at the higher raised temperatures. Only when the rail breaks in very cold weather will the rail temperature stresses be taken by the outrigger arm ends 35 and transmitted to the respective main carrier section 11, by the drawing back of the respective rail end.

25 I claim:

1. In a supporting structure for the rails of a suspended railway, a sectionalized main carrier frame, a unitary rail, and means for supporting said rail upon said frame, comprising a plurality of carrying members, and transmission members secured to said frame and having one end free for horizontal displacement cooperating with the frame upon abnormal longitudinal stressing of said rail, to limit the displacement of any portion of said rail relative to its corresponding frame section.

2. In a supporting structure for a suspended railway, a sectionalized main carrier frame, a unitary rail, lateral carrying members secured to said rail and secured to said frame, the end of said member secured to said rail being free for displacement longitudi-

nally of said rail strut structures secured to said rail and to said frame, there being at least one such structure to each section of said frame, and transmission members pivoted to said rail and arranged to bear against a portion of said frame upon abnormal longitudinal stressing of said rail.

3. In a supporting structure for a unitary member of considerable length, a sectionalized main frame, means for supporting said unitary member upon said frame, and means at the ends of each section of said main frame connecting said unitary member to the respective sections, said connecting means being normally inoperative to transmit longitudinal stresses between said member and frame but operative, upon abnormal stressing of said unitary member to transmit longitudinal stresses from said member to said frame.

4. In a supporting structure for a unitary member of considerable length, a sectionalized main frame, means for supporting said unitary member upon said frame, said means including strut elements disposed at an intermediate point of each section of said main frame for resisting relative longitudinal displacement of those portions of said unitary member associated with the respective strut elements, and means at the ends of each section of said main frame connecting said unitary members to the respective sections, said connecting means being normally inoperative to transmit longitudinal stresses between said member and frame but operative, upon abnormal stressing of said unitary member to transmit longitudinal stresses from said member to said frame.

5. In a supporting structure for the rail of a suspended railway, a sectionalized main carrier frame, strut elements disposed at an intermediate point of each section of said frame for securing said rail against normal longitudinal displacement relative to said frame, and transmission members disposed at the ends of each section of said frame, said members being pivoted to said frame and to said rail and positioned to bear against said frame upon abnormal longitudinal stressing of said rail, whereby to transmit said longitudinal stresses from said rail to said frame.

In testimony whereof I have affixed my signature.

FRITZ HEYNER.
